(No Model.)

N. NEWMAN.
AUTOMATIC GAS EXTINGUISHER.

No. 425,953.

Patented Apr. 15, 1890.

UNITED STATES PATENT OFFICE.

NELSON NEWMAN, OF SPRINGFIELD, ILLINOIS, ASSIGNOR OF TWO-THIRDS TO
GEORGE A. SANDERS AND SAMUEL J. WILLETT, BOTH OF SAME PLACE.

AUTOMATIC GAS-EXTINGUISHER.

SPECIFICATION forming part of Letters Patent No. 425,953, dated April 15, 1890.

Application filed September 30, 1889. Serial No. 325,550. (No model.)

To all whom it may concern:

Be it known that I, NELSON NEWMAN, of Springfield, county of Sangamon, State of Illinois, have invented a new and useful Improvement in Automatic Gas-Extinguishers; and I do hereby declare that the following is a full, clear, and exact description of my invention, which will enable others skilled in the art to which it pertains to make and use it, reference being had to the accompanying drawings, forming a part thereof.

My invention relates to an improvement in automatic gas-extinguishers adapted to be used on street-lights and for other similar purposes; and it consists in the peculiar construction and combination of devices that will be more fully set forth hereinafter, and particularly pointed out in the claims.

In the accompanying drawings, Figure 1 is a side elevation, partly in section, of an automatic gas-extinguisher embodying my improvements. Fig. 2 is a transverse sectional view of the same, taken on the line $x-x$ of Fig. 1 and illustrating the construction of the clamp. Fig. 3 is a similar view taken on the line $y-y$ of Fig. 1.

In the box A, which is rectangular in form and of any suitable size, is arranged a suitable clock-work mechanism or other motor, (not shown,) the shaft a of which is adapted to rotate once in twelve hours. To the outer end of the said shaft is affixed a circular disk b , having a series of twelve openings c near its periphery, arranged at regular distances apart and numbered, as shown, to indicate the hours. A tappet-pin d is adapted to be inserted in either of the said openings for the purpose to be presently described.

The gas or gasoline pipe has two sections e f arranged at right angles to each other and connected together by the coupling g . To the upper end of the vertical section f is attached a burner h , which may be of any desirable construction, and the said burner has a threaded opening i at right angles to and intersecting its bore. In the said threaded opening is arranged a screw-cock l , hav-

ing at its projecting end an arm m . When the said cock is turned in one direction, its threaded stem moves outward and opens the bore of the burner to permit the flow of gas therefrom, and when the cock is turned in the reverse direction its threaded stem closes the bore of the burner and cuts off the flow of gas, as will be apparent.

To the lower side of the box is attached a cylindrical clamp n , having the hinged lower member o , which is adapted to be opened to receive the horizontal section e of the gas-pipe and to be closed on the same. Lips p are formed at the outer sides of the members of the clamp, and a binding-screw r engages threaded openings in said lips, and serves thereby to clamp the sections securely on the pipe, and thereby attach the apparatus firmly thereto. It will be noted by reference to Fig. 1 that when the apparatus is thus arranged in position the arm l of the cock is in the path of the tappet-pin, so that when the disk is rotated the said arm will be engaged by the said pin. Before the gas is lighted the cock must be turned by hand to the open position, and the clock-work mechanism being set in motion the tappet-pin will be placed in the opening corresponding to the hour at which it is desired to extinguish the light. We will assume that the ninth hour is selected and the pin inserted in opening 9. This being done, the flow of gas will be permitted until the allotted time has expired, when the revolving disk will bring the tappet-pin in contact with the arm l , and as the said pin passes the said arm the latter will be caused to turn the cock to the closed position, and thereby extinguish the light.

Having thus described my invention, I claim—

1. The automatic gas-extinguisher comprising the box having the clamp to secure it to the gas-pipe, and provided, further, with a time mechanism having the revolving time-disk b arranged on one side, said time-disk having the openings c and the tappet-pin ad-

justable in said openings, and the burner having the cock provided with the arm *m* arranged in the path of the tappet, all adapted to operate substantially as described.

5 2. In combination with the burner having the cock provided with the arm *m*, the time mechanism having the time-disk *b*, provided with openings *c*, and the tappet-pin *d*, ad-

justable in said openings and arranged in the path of the arm *m*, substantially as described. 10

In testimony that I claim the foregoing I hereunto append my signature.

NELSON NEWMAN.
